UNITED STATES PATENT OFFICE.

HARRY F. WATERS, OF ST. LOUIS, MISSOURI.

NECKTIE.

Application filed November 18, 1925. Serial No. 69,842.

This invention relates generally to neckties and particularly to a necktie which is so constructed that said necktie will, upon being untied, return to its original un-
5 wrinkled condition.

Briefly stated, my improved necktie comprises the usual outer casing of fabric with-
in which is arranged a liner. The liner forming a part of my improved necktie
10 may be composed of one or more strips of woven fabric with which elastic compound is associated, said elastic compound being
preferably forced between the threads comprising said strip or strips of woven fabric
15 under pressure. The presence of the elastic material in the liner of my improved necktie gives to said liner just enough elasticity to cause said liner and the necktie casing surrounding same to return to their original
20 unwrinkled condition when the necktie has been untied.

I am aware that it is not new to sature a necktie liner with a solution containing a very small amount of rubber, but the
25 solutions used heretofore were so constituted that the major portions thereof comprised oils, such as linseed oil, in such quantities that liners treated with said solutions were not rendered sufficiently elastic to accom-
30 plish the results realized in connection with the use of a necktie made in accordance with the present invention. The solutions mentioned above were intended primary as toughening agents which would so prepare
35 the liner of the necktie that said necktie as a unit would be much less likely to tear. For a solution or compound to function as desired in accordance with the present invention, a very substantial amount of elastic
40 material must be present therein, and this is not so in connection with the solutions known heretofore. The solution or compound used in treating the liner of my improved necktie is made up of a high per-
45 centage of elastic material, there being present with said elastic material only such elements as curing agents, etc., which are necessary to properly compound the elastic material. In view of the foregoing the liner
50 of my improved necktie may be provided with the desired elasticity by the use of a relatively small amount of solution or compound, thus rendering the liner light in weight and comparatively soft. Also, it is
55 highly desirable that a necktie liner having an amount of elastic material associated

therewith be so made that the elastic material is not visible in sheet form, as said elastic material in that form detracts from the appearance of the liner. In accordance 60 with my invention, therefore, I produce a necktie provided with a liner comprising one or more strips of woven fabric having elastic compound associated therewith, said elastic compound being preferably forced under 65 pressure between the threads of said strip or strips of fabric, and because the liner is fuzzy at its front face the loose fibers will tend to conceal the elastic compound between the threads of the woven fabric at said front 70 face of the liner. The method of treating fabric by forcing elastic compound between the threads thereof is known as frictioning and when followed no material is forced into the threads, said elastic material being forced only between the threads of the fab-
75 ric.

A necktie having a liner made in accordance with my invention will return to its unwrinkled condition upon being untied, 80 and because the elastic material is present at both faces of the liner and is not arranged in the form of a layer on one face only thereof as has been done in the past, there is no tendency for the liner to curl due to the contraction or shrinkage of the material of one surface of the liner more than that of the opposite surface.

Fig. I is a plan view of a necktie made in accordance with my invention, a portion 90 of the outer casing of said necktie being broken away to show the liner thereof, which is composed of a plurality of strips of woven fabric frictioned with elastic material.

Fig. II is an enlarged cross-section 95 through the necktie shown in Fig. I.

Fig. III is a cross section through a necktie having a liner formed of one layer of fabric.

Fig IV is a greatly enlarged cross-section 100 taken through a fragment of the liner shown in Fig. III and showing the elastic material located between the threads of the fabric comprising said liner.

Fig. V is a greatly enlarged cross-section 105 taken through a liner comprised of a pair of strips of fabric secured together by the elastic material within said strips of fabric.

In the drawing A designates my improved necktie, which comprises the usual outer cas-
110 ing of fabric B which is ordinarily arranged in tubular form. Located within the outer

casing B is a liner C which may be the approximate shape of the inside of the tubular outer casing and is of slightly less length than said outer casing.

5 The liner C may be formed of one strip of woven fabric as shown in Figs. III and IV, or said liner may be formed of a plurality of strips of woven fabric as shown in Figs. I, II and V. In either event the strip or 10 strips of woven fabric have associated with them elastic compound D which may be forced by means of pressure between the threads comprising said strip or strips of woven fabric. When I employ a pair of 15 strips of woven fabric in producing the liner of my improved necktie a layer of elastic material may be interposed between the strips of fabric, as indicated by the reference character E in Fig. II, or a pair of 20 strips of fabric having elastic material therein may be forced together so that the elastic material within said strips of fabric will act as a binder to secure the strips together as shown in Fig. V. The liner of my improved necktie is provided with just enough 25 elastic material to cause said liner to return to its original unwrinkled condition when the necktie has been untied.

In producing the liner of my improved 30 necktie the strip or strips of woven fabric are preferably frictioned with elastic compound. In this case elastic compound, for instance rubber, which is combined with a curing agent is forced, by means of suitable 35 pressure-exerting devices, between the threads of the strip or strips of woven fabric. It is important to note in connection with the frictioning process that the elastic material is not forced into the threads of the woven 40 fabric but only between and around said threads. In producing the liner of my improved necktie which is formed of one strip only of woven fabric, cloth having a fuzzy front surface is preferably employed. The elastic 45 compound is preferably forced between and around the threads comprising the liner from the back of said liner, at which face the liner is not fuzzy. The elastic compound is forced entirely through the woven 50 fabric liner, in other words, said elastic material extends from the back face of the liner to the front face thereof, but because of the fuzzy condition of the liner at the front face thereof the loose fibers on the 55 threads will tend to cover the elastic material between the threads, thus making said elastic material practically invisible at the front face of the liner. Also, because the elastic material extends entirely through the woven 60 fabric liner said elastic material will be present at both faces of said liner, and consequently any tendency toward contraction or shrinkage of the opposite sides of the liner will be equalized.

65 When the liner of my necktie is made as

shown in Figs. I and II, a strip of woven fabric 1, which is provided with a fuzzy surface 1', is employed. The strip of woven fabric 1 is frictioned with elastic compound as already described, said elastic material 70 being forced through from the relatively smooth back face of said strip of fabric, and the loose fibers will conceal the elastic material at the fuzzy surface of said strip of fabric. A second strip of woven fabric 2, 75 which is provided with relatively smooth faces and which has preferably been previously frictioned with elastic material as already explained, is arranged adjacent to the first mentioned strip of fabric. Located 80 between the strips of fabric 1 and 2 is the elastic compound E already mentioned, said elastic compound, in addition to giving elasticity to the liner, acting as an adhesive whereby said strips of fabric are secured 85 together. The liner illustrated in Figs. I, II and V and just described functions in a manner to cause all wrinkles to be removed from the necktie when said necktie has been untied because of the presence of the elastic 90 material in the liner, and due to the fuzzy condition of the liner at the front face thereof the elastic material is practically invisible at that face. Also when a pair of strips of fabric is employed to form the liner I 95 may omit the elastic material E mentioned above and rely on the elastic material within the strips of fabric to secure said strips together, as shown in Fig. V.

It is to be understood that I do not limit 100 myself to the use of any particular elastic material, and while I find that rubber compound functions in a highly desirable manner I reserve the right to employ any elastic material which may prove suitable.

In the use of the necktie made in accordance with my invention a smooth knot may be tied, due to the presence within the tie of a liner having considerable body, and because of the elastic material associated with 110 said liner all wrinkles will be removed from the necktie when said necktie has been untied. This application is a continuation in part of an application filed by me on January 26, 1925, and which bears Serial Number 4,753.

I claim:

1. A necktie liner comprising a strip of fabric and a compound associated with said fabric, said compound being present only 120 between the threads of said fabric so that the liner has the outward appearance of a simple untreated strip of fabric, said compound being characterized by its tendency to resist wrinkling.
2. A necktie comprising an outer casing, and a liner within said outer casing, said liner comprising a strip of woven fabric, and elastic compound associated with said fabric, said elastic compound being present 130

only between the threads of said fabric so that the liner has the outward appearance of a simple untreated strip of fabric.

3. A necktie liner comprising a strip of woven fabric having a fuzzy surface, and elastic compound associated with said fabric, said elastic compound being present only between the threads of said fabric and the loose fibers at the fuzzy surface of said fabric tending to conceal the elastic compound so that the liner has the outward appearance of a simple untreated strip of fabric.

4. A necktie liner comprising a strip of woven fabric, and rubber compound associ-

ated with said fabric, said rubber compound being present only between the threads of said fabric so that the liner has the outward appearance of a simple untreated strip of fabric.

5. A necktie comprising an outer casing, and a liner within said outer casing, said liner comprising a pair of strips of fabric, elastic compound present between the threads in each of said strips of fabric, said elastic material acting as an adhesive which secures said strips of fabric together.

In testimony that I claim the foregoing I hereunto affix my signature.

HARRY F. WATERS.
